UNITED STATES PATENT OFFICE.

EDWARD C. KAHN, OF MILWAUKEE, WISCONSIN.

SPARK-PLUG.

1,359,996.

Specification of Letters Patent. Patented Nov. 23, 1920.

Application filed June 24, 1919. Serial No. 306,374.

To all whom it may concern:

Be it known that I, EDWARD C. KAHN, a citizen of the United States, and resident of Milwaukee, in the county of Milwaukee and State of Wisconsin, have invented certain new and useful Improvements in Spark-Plugs; and I do hereby declare that the following is a full, clear, and exact description thereof.

10 My invention relates to new and useful improvements in spark plugs for the cylinders of internal combustion engines.

The salient difficulty in insuring the provision of an adequate and reliable spark in 15 the cylinder of an internal combustion engine resides in the tendency of oil and carbon to accumulate on the electrodes, the oil forming an insulation against the free passage of the current, while the carbon constitutes a ready conductor tending to reduce or eliminate the spark gap, and the various conventional makes of spark plugs, while fairly reliable in operation when the engine cylinder is clean, become gradually coated 25 with carbon at their sparking points and thus suffer a loss of efficiency, particularly under the conditions of excessive oil or carbon deposit which are oftentimes encountered.

30 It is therefore the object of my invention to provide a spark plug wherein the electrodes are so arranged as to prevent interference with their sparking action by oil or carbon deposit, and it is more particularly 35 my object to provide maximum coacting sparking expanses of the electrodes to insure opposed active sparking surfaces at all times and to provide a maximum size of spark.

It is further my object to provide an arrangement wherein the sparking surfaces of 40 the electrodes are shielded from a dripping action of oil or condensed fuel which may accumulate upon other portions thereof.

It is still further my object to increase 45 the intensity and size of the spark by providing for the accumulation of electricity on a spherical electrode surface from which the spark may jump at any point in an annular line.

50 With the above and other objects and advantages in view, which will be apparent as the description proceeds, my invention resides in the novel features of construction, combination and arrangement of parts 55 which will be hereinafter more particularly

described and defined by the appended claims.

In the accompanying drawings:

Figure 1 is a side elevational view of a spark plug, with its lower portion in section 60 to show my improved electrode structure.

Fig. 2 is a bottom view of the spark plug.

Referring now more particularly to the accompanying drawings, 5 designates the ordinary metallic shell or casing of a spark 65 plug, said shell being threaded for engagement with the cylinder of an internal combustion engine, and forming the ground connection for the plug. The usual insulating filler 6 is disposed within the shell, 70 through which extends the usual insulated stem 7.

In the present embodiment of my invention, the lower end of this stem is enlarged in inverted cup-shape to form a female electrode 8, which receives in spaced relation to its inner surface, a spherical male electrode 9 carried by a rod 10 depending from the shell 5, said rod being bent inwardly and then upwardly to support the electrode 9 in 80 proper position. The inner surface of the female electrode 8 is partly spherical in contour, the curvature of said surface being such with respect to the curvature of the spherical male electrode 9 that the radial 85 distances between the surfaces are progressively increased toward the center of the female electrode and the edge or mouth portion of the cup of the female electrode is disposed at proper sparking distance from 90 the adjacent surface of the male electrode, thus defining an annular spark gap. The diameter of the mouth of the female electrode is slightly greater than the diameter of the male electrode, and thus any oil or 95 condensed fuel which may accumulate on the female electrode will not drip upon the male electrode, which is thus shielded.

In the operation of my improved spark plug, as the spark impulse is transmitted 100 to the positive electrode, the electricity will spread and accumulate on the spherical surface of said electrode and will then jump through that portion of the annular sparking space between the electrodes, which is in 105 most favorable condition at the moment of sparking, and the spark in jumping will spread about the annular sparking surface to procure an adequate expanse of the spark. Efficient and reliable operation of the plug 110

is thus insured, particularly by reason of the provision of an annular sparking space wherein the most favorable portion may be utilized at each spark period for transmission of the spark, it being noted that due to the explosion condition in the engine cylinder, the condition of the electrode face portions defining the sparking space would vary, but at least one portion would be in proper condition to transmit the spark.

While I have shown a preferred embodiment of my invention as comprising a male spherical electrode engaged in a cup-shaped female electrode, it will be appreciated that an important feature of my invention resides in the provision of spaced opposed annular electrode surfaces, and the structure may be varied within the scope of the appended claims, to meet differing conditions of use and manufacture without departing in any manner from the spirit of the invention.

What is claimed is:

1. A spark plug including a cup-shaped female electrode member, and a male elec-

trode member having a portion extending into the female electrode member and spaced from the mouth of the female electrode member to define an annular spark gap, the radial distances between the surface of the electrode member being progressively increased toward the center of the female electrode member.

2. A spark plug including a casing, an insulated stem extending through the casing, an inverted cup-shaped electrode carried by said stem, and a spherical electrode carried by the casing below the cup-shaped electrode with its upper portion extending into the cup-shaped electrode and spaced therefrom to define an annular spark gap, the diameter of the mouth of the cup-shaped electrode being greater than the diameter of the spherical electrode.

In testimony that I claim the foregoing I have hereunto set my hand at Milwaukee, in the county of Milwaukee and State of Wisconsin.

EDWARD C. KAHN.
